SAFETY HELMET

Arthur G. Gross, Torrance, Calif., assignor to Protection Inc., Inglewood, Calif., a corporation of California

Application February 18, 1954, Serial No. 411,163

2 Claims. (Cl. 2-3)

This invention relates to safety helmets of the type worn by construction workers, auto-racing drivers, and other persons involved generally in hazardous activities. More particularly, it has to do with a novel energy absorbing means incorporated in the helmet for effecting maximum energy absorption from blows whereby the best possible head protection for a given helmet size is attained.

Heretofore, there has never been to applicant's knowledge, a scientific, methodical approach to the designing of crash or safety helmets. In the past, such helmets have generally comprised a hard shell incorporating suspension straps adapted to rest on the wearer's head. A suitable space between the inner dome surface of the shell and the top of the wearer's head is maintained by these straps. This space will permit movement of the outer shell under an impact and thus prevent the dome frame striking the wearer's head provided the energy of the impact does not exceed the energy absorbable by the supporting straps and the dome structure. The energy that may be absorbed by the helmet is a function of the referred to spacing between the head straddling portions of the straps and the shell, and the resiliency or tension characteristics of the supporting straps.

In some prior art approaches to the design of a helmet for properly absorbing the energy of blows received thereby, there has been incorporated in the straps themselves or between the straps and the shell some type of elastic or resilient material that will "give" in the manner of a spring, following fairly closely Hooke's law. The product of the integrated force exerted by such material and the distance through which such force acts defines the absorbable energy. The available distance through which such integrated force can act in the case of the helmet is the distance between the straps and the shell. Any increased movement beyond such available distance will result in the impact being communicated to the wearer's head with consequent injury.

Because of the elastic properties of the straps or compression materials, the initial energy absorption is relatively small and precious space is used up. As the elastic materials stretch or are compressed, however, the forces increase and more energy is absorbed as the remaining available space is used. As a result of this distribution of the energy spectrum, a force of sufficient magnitude to fracture a person's skull or break his neck may be reached before sufficient energy from the impact has been absorbed. This force at which serious injury to the head will result is referred to hereinafter as the threshold force.

It is evident from the above, that best potential protection will be afforded by a helmet which is designed to absorb all the energy of the impact before forces in the helmet strap structure exceed the threshold force.

Generally, any impact received by a helmet will fall between two extreme conditions, to wit: (a) impact by a large blunt mass of relatively low velocity, and (b) impact of a small penetrating mass of high velocity.

2

The design of a suitable protective helmet must take into account these two conditions. In the first case of impact by a large mass of relatively low velocity, little change in velocity of the impacting body will occur due to the relative masses. Forces set up in the helmet and supporting strap structure therefore result predominantly from acceleration of the wearer's head and body resulting from the impact. Under these conditions, the primary function of the helmet is to permit acceleration of the head and body from the path of the impacting body without the setting up of forces greater than the referred to threshold force. It is to be noted that any local deformation of the dome or shell portion of the helmet relative to the head and straps at a force appreciably below the threshold force will result in the using up of some of the available space for energy absorption and may, therefore, be considered as a loss of the maximum potential protective performance of the helmet. Accordingly, the first step in the design of the helmet is the provision of an extremely rigid shell whereby substantially no local indentations occur but rather all forces are communicated to the supporting straps.

In the second case of impact by a small mass of high velocity, it is assumed that the total force on the head at no time exceeds the threshold force. The function of the supporting straps under these conditions then, is to maintain the maximum available spacing or distance between the head and shell whereby if partial penetration of the mass through the shell occurs, the chances of the body contacting the head are minimized. Any displacement of the shell relative to the head under forces less than the threshold force may thus also be considered a loss of the maximum potential protective performance of the helmet.

In each extreme case, and in intermediate conditions, it is seen that best protection is realized when the helmet is constructed to absorb a maximum amount of energy within the available space. With such an arrangement, there is greatly decreased the possibility of the threshold force being exceeded during normally contemplated impacts.

Bearing the above principles in mind, the primary object of the present invention is the provision of a safety helmet incorporating energy absorbing means of novel construction whereby the helmet structure can absorb considerably more energy without exceeding a given threshold force and within a given available spacing between the wearer's head and the helmet shell, than has heretofore been possible.

Briefly, this object is realized by avoiding the use of elastic or resilient energy absorbing materials, and substituting in lieu thereof elements or materials which will yield only when a given force is attained. This given force is calculated to have a magnitude slightly less than the threshold force in order to provide a safety margin but inasmuch as it is substantially constant, its action through a given distance results in maximum energy absorption within said distance.

The theory and principles underlying the invention, as well as some preferred embodiments thereof, will be better understood by referring to the accompanying drawings in which:

Fig. 1 is a schematic diagram of one type of known helmet;

Fig. 2 is a graph illustrating the energy absorbing characteristics of the helmet of Fig. 1;

Fig. 3 is a schematic drawing of a helmet constructed in accordance with the present invention;

Fig. 4 is a graph illustrating the energy absorbing characteristics of the helmet of Fig. 3;

Fig. 5 is an elevational cross-section view of a pre-

ferred helmet construction in accordance with the invention;

Fig. 6 illustrates in cross-section a plan view of the helmet of Fig. 5;

Fig. 7 is an enlarged elevational view of one type of energy absorbing means employed in the helmet of Fig. 5;

Fig. 8 illustrates a modified type of energy absorbing means which may be substituted for the element shown in Fig. 7;

Fig. 9 shows how the device of Fig. 8 appears after it has yielded or absorbed energy;

Fig. 10 illustrates a third embodiment of the energy absorbing means in exploded view;

Fig. 11 is a cross-section taken along the line 11—11 of Fig. 10; and,

Fig. 12 is another view of the device of Fig. 10 useful in explaining its operation.

Referring now to Fig. 1, there is shown a conventional helmet comprising a hard dome or shell 10 and a suspension or supporting strap 11. Strap 11 is secured in any suitable manner to the inside periphery of the helmet brim in a manner to leave a given spacing X_0 between the head-straddling portion thereof and the shell 10. This distance X_0 is hereinafter referred to as the available distance or spacing.

In most prior art safety helmets, the energy of an impact is absorbed by a stretching of the supporting straps. This stretching is accommodated by the distance X_0 . In some instances, elastic material is incorporated in the straps themselves or between the straps and the shell. In any case, the "giving" of the straps under impact is essentially an elastic phenomenon in which Hooke's law is followed reasonably closely. In Fig. 1, this elastic characteristic, however achieved, is symbolically represented by the small springs 12.

Fig. 2 is a graph of force vs. distance, the force scale being represented by the ordinate axis F and the distance through which the force acts being represented by the abscissa axis X. The curve 13 represents the variation of force due to impact on the shell 10 of the helmet with the distance between the shell and the wearer's head. This curve, for the sake of simplicity in illustrating the underlying theories of the invention, is shown as a straight line, as would be the case if Hooke's law were followed exactly. In reality, the curve for a conventional helmet would start with a more gradual slope and increase in slope at the upper end, being more or less concave in shape.

The available distance is designated on the abscissa scale in Fig. 2 as X_0 . It will be noted that since curve 13 is shown for convenience as essentially rectilinear, the slope thereof is equal to the net "spring" constants of the springs 12. It will be immediately evident that the shaded area under curve 13 between the limits O and X_0 represents the maximum absorbable energy by the helmet of Fig. 1.

Now if F_0 represents the threshold force or force at which the wearer's skull will fracture or neck be broken, it will be evident that, for an impact whose total energy is represented by the shaded area in Fig. 2, the force in the straps and thus imparted to the wearer's head will exceed the threshold force F_0 at the point X_1 . This distance X_1 is less than the available distance X_0 and therefore the available distance has not been employed to maximum advantage. The proportion of energy absorbed by the helmet before the threshold force is reached is given by the area under curve 13 between the limits O and X_1 . The present invention is primarily concerned, therefore, with increasing the amount of energy that can be absorbed before the threshold force is reached.

This increase in the absorbing property or protection potential of the helmet is accomplished as follows: Referring to Fig. 3, instead of springs 12, there is incorporated in the straps an energy absorbing means in the

form of yieldable elements 14. These elements are constructed to yield only when a certain predetermined force has been attained, and then to yield uniformly under a substantially constant force.

As shown in Fig. 4, this predetermined force is designated F_1 and is adjusted to a magnitude slightly less than the threshold force F_0 . Under these circumstances, there will be no appreciable stretch in the straps until the force F_1 is attained, at which time, the straps will yield uniformly until the available distance X_0 is used up. This characteristic is represented by the curve 15 of Fig. 4. It will be noted that there is an initial slope to this curve. This slope is greatly under-exaggerated for purposes of clarity; it represents the initial elastic properties of all materials which when subjected to a force will give in accordance with Hooke's law until the elastic limit is reached at which time they yield. Actually, the level portion of the curve 15 for some materials may have a slight slope, since, even in yield, some materials will exhibit some elastic properties. This slight slope is of negligible importance, however.

From an examination of the shaded area under curve 15, it will be seen at once that considerably more energy is absorbed within the distance X_1 as compared to Fig. 2, and that at no time, is the threshold force exceeded. Thus, the helmet of Fig. 3 could absorb the total energy of the impact without exceeding the threshold force F_0 of Fig. 2, the energy defined by the area of the triangle T being absorbed within the area under the curve 15 of Fig. 4 between the limits O and X_1 . This additional ability to absorb energy is the direct result of the yielding characteristics of the energy absorbing means 14. As stated, these elements do not operate in accordance with Hooke's law but are designed to operate beyond the elastic limit and thus yield, resulting in a plastic deformation thereof. The yielding which takes place under a constant force of predetermined magnitude results in the level characteristic of the curve 15. It is this energy absorbing characteristic as depicted in the graph of Fig. 4 which distinguishes the present invention from all prior art shock absorbing means incorporated in safety helmets.

Figs. 5 and 6 illustrate a preferred form of energy absorbing means and the manner of incorporating the same in the strap supporting portions of a helmet. As shown, the preferred type of helmet comprises straps 21, 22, and 23. These straps each have their opposite ends secured to one end of a yieldable element 24, the other end of the yieldable element being secured to the inside of the helmet brim as at 25. A conventional type sweat band or padding 25a covers the connections 25 to provide a comfortable cushioning against the sides of the wearer's head.

Each of the energy elements 24 are identical and description of one will suffice for all. Referring to Fig. 7, the element 24 is shown as comprising a tab or plate 26 having slotted opening 27 to which the end of one of the straps such as 22 is secured. The other end of the element 24 comprises a tab or plate 28 secured to the helmet brim at 25. Between plates 26 and 28 there are secured a plurality of helically wound steel wires 29. The windings are such that there is little if any elasticity in the helical windings, but their number and the diameter of the coils may be adjusted to vary the force at which these wires will plastically deform under tension. Thus, the predetermined force at which the element 24 will yield can be accurately adjusted by the number and proper dimensioning of the wire coils. As stated, this force is adjusted to a value slightly less than the threshold force to provide a safety margin. In practice, the ratio of the outside diameter of the helical coil to the wire diameter is made as small as possible and with maximum pre-loading so that the coil will immediately begin to yield when the proper force is attained.

In operation, when an impact is received by the helmet shell 20 of Fig. 5, the forces of the impact will be borne

by the straps until the predetermined force F_1 is reached. During this period very little, if any, of the available space X_0 will be used up. When the force F_1 is reached, however, the wires will yield under this force uniformly and they will thus absorb energy as they stretch through the available distance. This absorption will be the maximum amount capable of being absorbed without exceeding the threshold force as indicated by the level or straight line characteristic of the curve 15 as explained above.

Fig. 8 illustrates another type of energy absorbing element which may be substituted for the coiled wires 29 of Fig. 7. In this latter embodiment there is provided a metal strip of a given thickness depending upon the predetermined force F_1 . Into the edges of this strip there are provided a series of cuts 31. Centrally of the strip there are provided additional cuts 32. The lengths of these cuts can be varied to vary the force at which the strip will yield.

Under action of an impact force, the strip 30 of Fig. 8 will yield only when a predetermined force has been attained. This plastic deformation or yielding results in the configuration illustrated in Fig. 9 which shows the strip after it has absorbed energy. The stretching force results in the cuts 31 and 32 separating to form V gaps 33 and diamond-shaped openings 34 respectively. It is 25 to be emphasized, that once the predetermined force has been attained the deformation continues under a constant force.

Figs. 10 to 12 illustrate yet another means of obtaining an energy absorbing characteristic as depicted in Fig. 4. In this embodiment, there is provided a channel element 35 adapted to be secured to the inside brim portion of the helmet as by fastenings 36. Channel 35 has its longitudinal edges 37 and 38 turned over to oppose one another to form a longitudinal slot 39 of narrower width than the channel. The suspension or supporting strap 22 of the helmet is secured to a button plate 40 from which there extends a shaft 41 having an enlarged head 42. The shaft 41 has a diameter slightly larger than the width of the slot 39, while the head 42 is dimensioned to ride within the channel of member 35 all as clearly shown in Figs. 11 and 12.

The end side portions of the walls 37 and 38 may be enlarged as at 43 and 44 (Fig. 10) to permit the button plate 40 to be initially snapped into position and 45 thus secured to the helmet brim.

When an impact force is set up in the supporting straps due to an impact on the shell of the helmet, the button plate 40 is pulled upwardly. The enlarged head 42 rides within the channel of the member 35 and guides this 50 motion. Because of the fact that the diameter of the shaft portion 41 is larger than the slot 39, the shaft will peel back the walls 37 and 38 as it rides upwardly.

The force necessary to effect this peeling is adjusted by making the walls of a specified strength and thickness, to equal the predetermined force desired. This force will be constant as the bottom plate moves along the 5 channel and thus a force-distance characteristic curve as shown in Fig. 4 is realized.

An advantage of the particular arrangement shown in Figs. 10 to 12 resides in the fact that the initial slope of the force-distance curve is exceedingly steep since 10 there is essentially negligible elastic action in the mechanism.

It will be understood, of course, that all of the yieldable elements described are expendable and once they 15 have absorbed energy a new element must be inserted in their stead.

It is also to be understood that the principles of energy absorption set forth above have application to other safety devices besides helmets such as safety belts employed by scaffolding workers. In any instance then, 20 where it is desired to absorb a maximum amount of energy within a given spacing without exceeding a given threshold force, the principles of the present invention are applicable.

I claim:

1. A safety device comprising: a helmet having a substantially rigid shell, suspension means secured to the shell and adapted to rest on a wearer's head and space the top of the wearer's head a given clearance distance from the interior surface of the shell, and a metal coil interposed in said suspension means to provide yieldability therein, the diameter of said wire and the diameter of said coil having values such that said coil exhibits elastic elongation substantially according to Hooke's law through a maximum distance materially less than said given clearance distance when subjected to a given tensile force and plastically elongates at substantially constant force in a range within the balance of said clearance distance when subjected to a tensile force greater than said given force.

2. The subject matter of claim 1, wherein a plurality of the metal coils as defined are arranged in parallel in said suspension means.
